ATTORNEY

UNITED STATES PATENT OFFICE

JOSEPH BRASTY, OF MAPLE HEIGHTS, OHIO, ASSIGNOR OF ONE-THIRD TO JULIUS B. LEWIS, OF CLEVELAND, OHIO, AND ONE-THIRD TO LEWIS COLTON, OF CLEVELAND, OHIO

VACUUM SWEEPER

Application filed June 21, 1929. Serial No. 372,691.

This invention relates to an improvement in vacuum sweepers.

One of the objects of this invention is to provide a simple and effective brush operating mechanism by means of which the brush has an oscillating motion which has a whisking effect on the carpet, etc. to be cleaned.

Another object of the invention is to eliminate the use of the rubber belt which is common to present day vacuum sweepers.

A still further object of the invention is to provide a vacuum sweeper having few parts and which are easily accessible and can be quickly changed.

Other objects will also be evident from the following description taken in connection with the drawings, which form a part of this specification, and in which:

Fig. 1 is broken sectional view of a vacuum cleaner showing the application of this invention.

Fig. 2 is a view taken on line 2—2 of Fig. 1 broken away, to show a plan view of the construction.

Fig. 3 is an enlarged perspective view of the brush operating device.

Fig. 4 is an inverted sectional view of the nozzle or suction head of the sweeper.

Fig. 5 is a perspective view of the pressure spring shown in Fig. 4.

Fig. 6 is a perspective view of inner bracket which holds the brush in position.

Referring to the drawings, Figs. 1 and 2 illustrate a vacuum sweeper having a motor 1, fastened to body 2 by bolts 3 and which has a dust bag 4 appended at the rear thereto and a foot 5 to which a roller 6 is attached for propelling the cleaner.

The forward brush housing 6 of vacuum chamber 7 has an inner bent or U-shaped bracket bar or holder 8 the main bar of which is offset at the middle and slotted at 9 to slidably engage pin 10 fixed in brush rod 11 the rod being held in position by means of openings 12 in the end walls 13 of the bracket

8 which fits closely at its ends in the housing 6 and is held in position by the pressure of a spring 31 causing notches 32 in the ends of the arms 13 to engage pins 33 projecting through the side walls of the housing 6.

The fan 14 having a plurality of curved fins 15, in revolving cause a suction of air through the brush housing 6 drawing dirt and other like substance through vacuum chamber 7 into dust bag 14 as it is swept up by the action of the plurality of brushes 16 that are fixed in or secured to brush rod 11.

The eccentric 17 has a smaller end 18 which is circled by the open end 19 of the end connection 20 of a connecting rod and is held in position by a cap 21.

The eccentric portions 17 and 18 and cap 21 have an opening 22 off center thru which bolt 23 is inserted and fastened to the fan 14.

The end connection 20 of the connecting rod 65 is connected to the flexible middle or spring portion 24 by means of a clip 25 and bolt, or rivet 26, the spring portion in turn being fastened to the opposite end connection 27 having at the extreme end an opening 30 thru which pin 10 extends, the end of the bar 27 working in the offset part of the bar 8.

As the fan 14 revolves the eccentric and connecting rod cause the pin 10 to slide in the slot 9 thus producing a sweeping movement of the brushes 16; the ends of pressure spring 31 pushing against housing 6 causes the center of spring to press against inner bracket 8 thus preventing vibration of the brush rod 11, and this spring also prevents displacement of the brush pin 10.

I claim:

1. The combination with the suction nozzle of a vacuum sweeper the side walls of the nozzle having inner projections, of an oscillating brush extending across the nozzle, a U-shaped bracket bar fitting in the nozzle and supporting the brush, the ends of said bar fitting against said side walls and having

notches in which said projections are engaged, and means to oscillate the brush.

2. The combination with the suction nozzle of a vacuum sweeper, of an oscillating brush extending across the nozzle, an inverted U-shaped bracket bar fitting in the nozzle and supporting the brush, the bracket bar having a slotted offset part at the middle, a pin projecting from the brush and through said slot, and means to oscillate the brush including a rod working in the offset of the bar and engaging said pin.

10 In testimony whereof, I do affix my signature.

15

JOSEPH BRASTY.
